UNITED STATES PATENT OFFICE

JEAN DELPHICE OLIGNY, OF MONTREAL, QUEBEC, CANADA, ASSIGNOR TO PEAT GAS AND COAL COMPANY, OF MONTREAL, CANADA, A CORPORATION OF MAINE.

PEAT-GAS PLANT.

938,691.

specification of Letters Patent. Patented Nov. 2, 1909.

Application filed February 4, 1909. Serial No. 470,114.

To all whom it may concern:

Be it known that I, JEAN DELPHICE OLIGNY, resident of 37A St. Augustin street, in the city and district of Montreal, in the Province of Quebec, in the Dominion of Canada, a subject of the King of Great Britain, have invented certain new and useful Improvements in Peat-Gas Plants; and I do hereby declare that the following is a full, clear, and exact description of the same.

The invention relates to improvements in peat gas plants, as described in the present specification and illustrated in the accompanying drawings that form part of the same.

The invention consists essentially in mixing air with the gas during the period of coking the peat and gathering by-products from the gas in its passage to the gasometer by means of the various devices employed and in addition augmenting the heat and light properties of the gas.

The objects of the invention are to produce a gas from peat at a very low cost, to provide a gas having good heating and illuminating properties and generally to utilize peat, of which there are such great quantities, in the most desirable and economical form.

In the drawings, Figure 1 is a diagrammatic view showing the arrangement of the several parts of the plant. Fig. 2 is a sectional detail of the retort.

Like numerals of reference indicate corresponding parts in each figure.

Referring to the drawings, 1 is the retort here shown as rotatable and as having the gas egress pipe 2 leading from a suitable opening in the head of said retort through the gland 3, said egress pipe meeting the stationary pipe 4 in said gland, the latter pipe 4 having an opening 5 thereinto.

6 is an air pipe leading from the air reservoir 7 through the opening 5 into the retort 1, said opening 5 being securely packed around said pipe 6 to prevent the escape of gas therethrough.

The stationary pipe 4 leads preferably in curved direction to the casing 8, the said casing 8 being surrounded by the water jacket 9 and filled with tar.

10 is the outlet opening from the casing 8. 11 is the overflow opening from said casing.

12 is the pipe from the overflow opening 11 leading to the receptacle 13 and extend-

ing into said receptacle below the liquid therein contained, said pipe 12 having the trap 14 intermediate of the length thereof.

15 is the main gas pipe leading from the opening 10 to the gasometer 16 and having the curved portions 17 and 18 forming the condensation portion of the plant, said curved portions having pipes 19 and 20 from openings in the lower and curved sides and said pipes 20 extending below the liquid level in the by-product tanks 21 and 22.

In the operation of this plant, the peat, previously crushed and during crushing saturated with petroleum, is placed in the retort and baked to a coke. During this baking process, the air is turned on from the reservoir 7 or any suitable air supply and passes into the retort through the pipe 6, thus becoming heated, while the peat is being baked, and mixing with the gas produced during the coking process. This operation is continuous, and the gas as produced is constantly flowing out of the opening and into the stationary pipe 4 from whence it flows through the tar or carbureting chamber contained in the casing 8, the gases passing through said tar into the main pipe 15 and through the condensing lengths of the pipe to the gasometer, in passage dropping the by-products into the by-product tanks 21 and 22.

The operation is continuous while the coking process is in progress, and as the said retort is arranged to be charged without any undue loss of time, the plant may be said to be kept in constant operation during the filling of the gasometer or gasometers as the case may be.

What I claim as my invention is:

1. In peat gas plants, the combination with a retort having a suitable outlet, of a casing containing a suitable carbureting chamber having an inlet and outlets, an air pipe leading from a suitable air supply into said retort, a pipe leading from said retort outlet to the inlet of said casing, a main gas pipe leading from an outlet of said casing, an overflow pipe leading from the other outlet of said casing, by-product pipes tapping said main gas pipe, and a gasometer.

2. In peat gas plants, the combination with a retort having a suitable outlet, of a casing containing a suitable carbureting chamber having an inlet and outlets, a water jacket surrounding said casing, a pipe leading from

the retort outlet to said casing inlet; a main gas pipe having condensing curved lengths and leading from a casing outlet, an overflow pipe from the other casing outlet, by-product pipes tapping said main gas pipe, and a gasometer.

3. In a device of the class described, in combination, a retort having an outlet and a pipe leading from said outlet, a stationary pipe leading from the aforesaid pipe and suitably packed, an air pipe leading through the latter pipe into the casing, an air reservoir, a tar chamber, a water jacket around said tar chamber, said stationary pipe leading into said tar chamber, a main gas pipe leading from said tar chamber and having

condensing lengths, by-product tanks, pipes leading from said main gas pipe into said by-product tanks, a gasometer, an overflow pipe leading from said tar chamber having a 20 trap portion intermediate of its length and a receptacle into which said overflow pipe extends.

Signed at the city and district of Montreal, in the Province of Quebec, in the Dominion of Canada, this 12th day of January, 1909.

JEAN DELPHICE OLIGNY.
